[57] CLAIM

The ornamental design for a shoe, substantially as
shown and described.

DESCRIPTION

FIG. 1 is a top plan view of a shoe showing my new
design;

FIG. 2 is a side elevation showing the right side thereof;

FIG. 3 is a bottom plan view thereof;

FIG. 4 is a rear elevation thereof;

FIG. 5 is a side elevation showing the left side thereof;
and

FIG. 6 is a front elevation thereof.

The portion of the shoe upper above the ankle is a
smooth finished texture, while the portions below the
ankle are rough textured.
